CLAIM

The ornamental design for a head for a shovel, as shown and described.

DESCRIPTION

FIG. 1 is a front elevational view of a head for a shovel showing my new design;

FIG. 2 is a right side elevational view thereof the left side being identical in appearance;

FIG. 3 is a rear elevational view thereof; and

FIG. 4 is a sectional view of the shovel head taken along line 4—4 of FIG. 1.
